UNITED STATES PATENT OFFICE.

JAMES M. CONNER, OF GREENVILLE, NEW JERSEY.

DESIGN FOR PRINTING-TYPE.

Specification forming part of Design No. **7,147**, dated January 27, 1874; application filed January 13, 1874.
[Term of Patent 7 years.]

To all whom it may concern:

Be it known that I, JAMES M. CONNER, of Greenville, Hudson county, New Jersey, have invented and produced a new and original Design for Printing-Type, of which the following is a specification:

The nature of my design is fully shown in the accompanying typographic impressions, to which reference may be had.

What I claim as new is—

The design for printing-type, as shown.

JAMES M. CONNER.

In presence of—

W.M. C. CONNER, JR.,
RICHD. W. MANNING.
